UNITED STATES PATENT OFFICE

2,094,948

APPARATUS FOR DIVIDING OR COMBINING
STREAMS OF FLUENT MATERIALSThomas Frederick Hurley and Robert Dickinson,
East Greenwich, London, EnglandApplication March 9, 1936, Serial No. 67,992
In Great Britain April 9, 1935

3 Claims. (Cl. 137—166)

This invention relates to apparatus for use in dividing or combining streams of fluent material as, for instance, for the purpose of mixing, sampling and distributing and as a burner for 5 gaseous liquid or pulverulent solid fuels in the production of diverging or dispersive or concentrated flame effects.

The object of the invention is to provide an improved apparatus for the purposes in question 10 enabling a stream or streams of fluent material to be sub-divided into a greater number of equal or unequal streams or to enable a number of streams to be combined into a single stream, in such manner as will ensure intimate mixing of 15 the material forming the individual streams or to enable a single stream of material which may have become stratified or otherwise segregated to be treated in order that its composition or constitution may be averaged or rendered substantially uniform.

The invention consists in apparatus for the purpose in question comprising one or more inlets or outlets for all of a plurality of ducts and having more than one outlet or inlet for such 25 ducts in such manner that no duct connects with more than one such outlet or inlet.

Preferably, apparatus in accordance with the invention comprises a plurality of sections of the character defined, in which the ducts of one section 30 communicate with a greater or less number of ducts in an adjacent section.

The ducts connecting one inlet or outlet with any given outlet or inlet may be regularly or 35 symmetrically spaced, arranged or interspersed with respect to the ducts connected with another outlet or inlet.

Thus, for instance, where the inlet or outlet is in the form of a parallelogram the ducts may be arranged to form rows parallel with two opposite 40 sides of the parallelogram the adjacent ducts in such individual rows communicating with different outlets or inlets.

Optionally, in accordance with the invention, where the apparatus comprises a plurality of sections, the ducts of one section communicating with a greater or less number of ducts in an adjacent section, the cross sectional area of the 45 ducts in the several sections may be varied for the purpose of promoting a constant velocity of flow 50 of material through the successive ducts.

To this end also or alternatively the form of the ducts in cross section may be modified.

Furthermore, the form of the ducts or certain 55 of them may be modified to secure a Venturi effect.

In some cases the ducts may be arranged to provide for the flow of the materials in a rectilinear path generally or in particular sections where a plurality of sections of the character above defined are provided. 5

Alternatively, the ducts may be curved so as to secure the flow of the materials in a generally non-rectilinear path.

In one form the invention may be described as covering apparatus having an inlet or outlet 10 divided into X groups each of Y ducts, each group having each of its Y ducts connected to one inlet of one of the X outlets or inlets. The arrangement of the ducts will normally be such that the entrances to the Y ducts of any of the X 15 groups are distributed over the cross sections of the conduit in such a manner that the material from adjacent ducts does not pass to the same outlet when the device is used as a distributor. The entrances to the X groups may or may not form 20 geometrically similar patterns when viewed along the direction of flow.

The invention may be conveniently illustrated by reference to its application as an apparatus for dividing a stream of air carrying powdered coal into two substantially equal streams for supplying two powdered fuel burners. Up to the present this has been a difficult problem owing to the varying distribution of the coal particles. It has been found by the inventors that if the main 25 conduit is divided by equidistant transverse partitions and the ducts thus formed are connected alternately to a second conduit leading to one burner and to a third conduit leading to the other burner, a substantially equal supply to both 30 burners is ensured. 35

In a preferred modification all the ducts in the first row are inclined to the right conveniently to the extent of half the width of one duct. The next row is inclined by a similar amount to the 40 left, the third to the right and so on. If the ducts are distinguished at their entry by the letters n , m used alternately horizontally and vertically, this displacement will have the effect of bringing all the n 's and all the m 's together in alternate 45 vertical rows at their exits. All the vertical rows of n 's and all the vertical rows of m 's can then be separately connected with the second and third conduits previously mentioned.

For convenience of description it has been assumed in the preceding paragraph that the inlet is horizontal. In practice any of the conduits may be at any desired angle with either the horizontal or vertical. Further, in the same paragraph it is, for convenience of description, said that the 50 55

alternate rows of ducts are inclined to the extent of half the width of one duct in either direction. In certain cases, for example when the apparatus is used for mixing, the inclination may be increased to any desired extent in order that filaments of the fluent material entering adjacent ducts may emerge from the outlets of the ducts as far removed as possible from one another.

As will be seen, this method of displacing the ducts can be used for the production of three or more streams. For example, if all the ducts in the first row are inclined to the right and those in the second row to the left and those in the third row are given no inclination, and this is repeated for every three rows, three groups of take-offs can be fitted to the outlets of the ducts in a manner similar to the previous examples where two sets of take-offs were used.

The ducts may be of any shape and instead of being formed by partitions may be formed as separate tubes of circular, hexagonal or other cross section. More than one shape of duct may be used, preferably, though not necessarily, arranged according to a definite pattern.

In the examples given the ducts have been distributed over the cross section of the original conduit as uniformly as possible, but the invention is not limited to a uniform distribution and, indeed, any distribution may be used, provided always that no duct is connected to more than one outlet.

Above the application of the invention in connection with burners for powdered fuel has been described. It is, however, to be noted that the invention is equally applicable in connection with burners with liquid or gaseous fuels or as sampling devices, or for any apparatus that requires a stream of fluent material to be divided into a number of equal or unequal streams.

The apparatus may itself be used as a burner for gas or pulverized fuel. Thus, if gas, with or without air, or air borne powdered fuel is introduced through the inlet it will emerge from the ducts divided into a number of groups of separate streams, the number of groups corresponding to the number of outlets when the device is used as a distributor. The outlets of the ducts can be arranged to communicate with a furnace, thus enabling the apparatus to be used as a dispersive burner. If desired, secondary air can be interspersed between the streams of fuel or fuel and air leaving the ducts.

Alternatively, by reversing the apparatus described above, it may be used for mixing two or more equal or unequal streams of fluent material.

The apparatus may also be used as a burner in its reversed form. For example making use of the modification in which the normal inlet is divided into a number of square ducts, one of the normal outlets may be supplied with fuel, with or without primary air, while another of the normal outlets is supplied with secondary air. With this arrangement the fuel, with or without primary air, will issue from the normal inlet in the form of a number of streams of square cross section, alternating with similar streams of secondary air, thus enabling the apparatus to be used as a burner.

Two or more of the above devices may be arranged in series in any desired manner. The output from any or all of the outlet conduits from the first apparatus may be passed through the second apparatus, or alternatively, the output from any outlet conduit may be circulated back to

be passed through any preceding apparatus again. When arranged in series, successive devices may or may not be of similar dimensions.

The invention will be described further in detail and by way of example with reference to the accompanying drawings, in which:—

Figure 1 is a view in elevation in one plane of an apparatus in accordance with the invention, in which the inlets and outlets and the individual ducts are in the form of rectangular parallelograms,

Figure 2 being a view thereof in elevation in a plane at right angles to Figure 1.

Figure 3 is a plan view of the uppermost section of the apparatus illustrated in Figure 1.

Figure 4 is a sectional elevation on the lines IV—IV of Figure 3,

Figure 5 is a corresponding view on the lines V—V of Figure 3,

Figure 6 is a sectional plan view on the lines VI—VI of Figure 1, and

Figure 7 is a sectional elevation on the lines VII—VII of Figure 1, while

Figure 8 is a sectional plan view corresponding with the sectional plan view in Figure 3 of an alternative construction by which a single stream of material is divided up to form three streams or three streams may be united to form a single stream.

Figure 9 is a section on the lines IX—IX of Figure 8, the sections on the lines IV—IV and V—V of this figure being generally as indicated in Figures 4 and 5.

In Figures 1 and 2, 1 represents the inlet which as shown in Figures 3—8 is divided up by walls 3 and 4 to form a plurality of ducts arranged in rows, the ducts 5, 5a, 5b, 5c, 5d, 5e and 5f forming rows alternating, in the case of the construction illustrated in Figures 3—5, with rows of ducts 6, 6a, 6b, 6c, 6d, 6e and 6f.

In the case of the construction illustrated in Figure 8, between each two of such rows of ducts there is arranged a further row of ducts 7, 7a, 7b, 7c, 7d, 7e and 7f. The walls dividing the individual ducts in the rows 5—5f and the rows 6—6f are inclined in reverse senses as may be seen from Figures 4 and 5, while the walls dividing the individual ducts in the rows 7—7f are arranged vertically as may be seen from Figure 9.

Alternate members of each of the horizontal rows of ducts in the case of a construction as illustrated in Figures 1 to 7 are arranged to communicate, so far as is possible, with the same duct of the next preceding or succeeding section.

Thus, all of the ducts 5a communicate with the duct 8a and all of the ducts 5b communicate with the duct 8b, all of the ducts 5c with the duct 8c, the ducts 5d with the duct 8d, the ducts 5e with the duct 8e, and the ducts 5f with the duct 8f, while the three ducts 5 communicate with the duct 8. In addition the ducts 6 communicate with 8a, the ducts 6a with 8b, the ducts 6b with 8c, the ducts 6c with 8d, the ducts 6d with 8e, the ducts 6e with 8f and the three ducts 6f with the duct 8g.

The ducts 8, 8b, 8d and 8f communicate in turn with the common duct or outlet 9 and the ducts 8a, 8c, 8e and 8g with the duct or outlet 10. In the case of the construction shown in Figure 9 a third outlet or inlet will be provided.

We claim:

1. Apparatus comprising a plurality of ducts, a plurality of intermediate ducts arranged in groups the number of which groups corresponds with the number of the first-mentioned ducts.

and with the ducts of each of such groups arranged in communication with only one of each such first-mentioned ducts, a plurality of terminal ducts arranged in a plurality of rows with the alternately located members of each row in communication with one only of the intermediate ducts and with the adjacent terminal ducts of an immediately neighbouring group in communication with a different intermediate duct.

2. Apparatus comprising a plurality of ducts, a plurality of intermediate ducts arranged in groups the number of which groups corresponds with the number of the first-mentioned ducts and with the ducts of each of the groups of intermediate ducts arranged in communication with only one of each of such first-mentioned ducts, a plurality of closely spaced terminal ducts arranged in a plurality of rows with the first, third, fifth and like odd numbered ducts of one row in communication with an intermediate duct of one group, and the second, fourth, sixth and like even numbered ducts of the said row communicating with an intermediate duct of a second group of such ducts, and the first, third, fifth and like odd numbered ducts of the second row, and the second, fourth, sixth and like even numbered ducts of a third row communicating with another intermediate duct of the last-mentioned

group of the first, third, fifth and like odd numbered ducts of the third row, and the second, fourth, sixth and like even numbered ducts of the fourth row communicating with an intermediate duct of the first-mentioned group thereof, and so on.

3. Apparatus comprising a plurality of ducts, a plurality of intermediate ducts arranged in groups the number of which groups corresponds with the number of the first-mentioned ducts and with the ducts of each of the groups of intermediate ducts arranged in communication with only one of each of such first-mentioned ducts, a plurality of closely spaced terminal ducts arranged in a plurality of rows with individual terminal ducts spaced apart at intervals in a row in communication with an intermediate duct of one group and the individual ducts located within such intervals in communication with an intermediate duct of another group and with the correspondingly spaced ducts in the next succeeding row communicating with the first-mentioned intermediate duct, the individual ducts in the succeeding row being correspondingly arranged in communication with intermediate ducts.
